FLEXIBLE STRAP FASTENER AND IDENTIFICATION BAND

Dwight C. Brown, 1516 N. Nicholas St.,
Arlington, Va. 22205

Filed Mar. 1, 1974, Ser. No. 447,302

Term of patent 14 years

Int. Cl. D9—06

U.S. Cl. D9—252

FIG. 2

FIG. 1 is a plan view of a flexible strap fastener and identification band showing my new design; and

FIG. 2 is an enlarged scale perspective view thereof shown in a closed or secured condition.

I claim:

The ornamental design for a flexible strap fastener and identification band, as shown and described.
